CLAIM

The ornamental design for a waste container lid, as shown and described.

DESCRIPTION

FIG. 1 is a perspective view of a waste container lid of our new design;

FIG. 2 is a front view showing our new design shown in FIG. 1;

FIG. 3 is a back view showing our new design shown in FIG. 1;

FIG. 4 is a top view showing our new design shown in FIG. 1;

FIG. 5 is a bottom view showing our new design shown in FIG. 1; and,

FIG. 6 is a left side view showing our new design, the other side view being identical.

The broken line showing in the figures is included for the purpose of illustrating environment and forms no part of the claimed design.
